CLAIM

The ornamental design for a gasoline pump island, substantially as shown.

DESCRIPTION

FIG. 1 is a front elevational view of a gasoline pump island showing my new design, the rear being a mirror image of that shown and the horizontal lining on the canopy being understood to represent the channeling shown enlarged in FIG. 3;

FIG. 2 is a top plan view thereof;

FIG. 3 is an enlarged side elevational view thereof, the opposite side being a mirror image of that shown; and FIG. 4 is a perspective view thereof.
